[57] CLAIM

The ornamental design for a bicycle pedal, as shown and described.

DESCRIPTION

FIG. 1 is a top front perspective view of a bicycle pedal showing our new design.

FIG. 2 is a bottom rear perspective view thereof.

FIG. 3 is a side elevational view, the opposite side being a mirror image thereof.

FIG. 4 is a top plan view on a reduced scale, the bottom plan view of which is the mirror image thereof.

FIG. 5 is a front end elevational view thereof on a reduced scale.

FIG. 6 is a rear end elevational view thereof on a reduced scale.

FIG. 7 is a top front perspective view of a second embodiment of a bicycle pedal showing our new design.

FIG. 8 is a bottom rear perspective view of the second embodiment of FIG. 7.

FIG. 9 is a side elevational view of the second embodiment of FIG. 7, the opposite side being a mirror image thereof.

FIG. 10 is a top plan view on a reduced scale of the embodiment of FIG. 7, the bottom plan view of which is a mirror image thereof.

FIG. 11 is a front end elevational view of the embodiment of FIG. 7 on a reduced scale.

FIG. 12 is a rear end elevational view of the embodiment of FIG. 7 on a reduced scale.
